CENTRIFUGAL PUMP

Giles Philip Eliot Howard, Amersham, England

Application May 5, 1942, Serial No. 441,842
In Great Britain May 5, 1941

12 Claims. (Cl. 103—102)

This invention relates to centrifugal pumps of the multi-stage type.

Pumps of this kind have hitherto been built up of parts comprising, for each stage, a suction chamber defining member, an impeller member and guide means for directing the liquid discharged from the impeller into the suction chamber of the next stage. In the case for instance of ordinary horizontal high lift turbo pumps, each stage comprises a bowl having passages designed to convert the high speed tangential flow from one impeller into an axial flow at the entry of the next impeller, the bowls being connected together in series; or alternatively, each stage comprises an impeller, a diffuser member taking the radial and tangential flow and converting it into a tangential and axial flow, and a third guide member which converts this latter flow into a purely axial flow at the eye of the next impeller. This arrangement is sometimes modified so that the diffuser vanes do not change the direction of flow entirely to the axial but merely reduce the tangential velocity, and in this case an outer chamber of semi-toroidal form is provided, to redirect the flow into the return guides which convert the flow into an axial flow at the eye of the next impeller.

In all such forms of construction external means have to be provided for assembling the stationary or guide members of the successive stages in end-to-end relationship, and for this purpose there are usually employed either an enveloping tubular member with compression means at the ends or long bolts passing outside or through holes in the guide members or studs and nuts at each stage to bolt it to the next. In every case, such securing means entail a substantial increase in the outside diameter of the pump, and any outside casing provided is extraneous to the essential component parts of the pump.

This general mode of construction is dictated by the assumed desirability of suppressing turbulence by curving the outer wall of the guide means by which the liquid flow is diverted between the point of leaving an impeller of one stage and entering the suction chamber of the next stage.

I have found that, given suitable arrangement and dimensioning of the guide means, this assumed requirement may be dispensed with, and that the diverting peripheral surface of the guide means may be normal to the radial planes of the pump assembly, without appreciable loss of efficiency. Consequently the guide

means may comprise juxtaposed sets of spiral or inclined vanes mounted in a peripherally open annular supporting structure and adapted to guide the discharging and entering flows tangentially, while the diversion therebetween is effected by a cylindrical wall suitably spaced from said sets of vanes.

From this it follows that the provision of an independent housing can be dispensed with and the required cylindrical wall may be formed on the housing itself which thus participates in the liquid guiding function.

The invention accordingly consists in a multi-stage centrifugal pump wherein the external housing itself forms part of the means for guiding the flow between successive stages.

In further development of the invention, the stationary parts of the pump are formed with cylindrical peripheral surfaces of the same diameter and the external housing consists of a single cylindrical member adapted to be simply fitted slidingly over the consecutively assembled parts of the pump, to complete the assembly.

It will be appreciated that in this way, a very great simplification of the work of assembly and dismantling is achieved, as compared with pumps having an extraneous sectional housing, quite apart from the fact that the construction of the individual parts is greatly simplified and the total amount of machining required is very materially reduced. Owing to the use of a one-piece cylindrical casing tightly embracing the stationary parts of the pump assembly, the present invention also enables the total weight of the pump to be substantially reduced without sacrifice of strength. Moreover, owing to the economy in diametrical dimensions achieved by the invention, the further advantage is obtained, that impellers of larger diameter may be used, resulting in a greater pressure gain per stage and enabling fewer stages to be used in a pump of given over-all diameter, with fewer parts and a shorter shaft.

In order that the invention may be more fully comprehended and readily carried into practice, an embodiment of its various features is illustrated, by way of example only, in the accompanying drawings, in which:

Figure 1 shows, in longitudinal section, a complete pump according to the invention, with a combined fluid admission and motor attachment piece fitted to the inlet end thereof;

Figures 2 and 3 show in axial section and in elevation respectively, one of the impellers of the pump;

Figures 4 and 5 are views also in axial sec-

tion and in elevation respectively of an intermediate guide vane member;

Figures 6 and 7 are respectively an axial sectional view and an elevation of the end bearing member or cap of the pump rotor;

Figures 8 and 9 are like views of the balance disc;

Figures 10 and 11 are like views of the balance seat; and

Figures 12 and 13 are like views of a diffuser member operative on the fluid on discharge from an impeller.

As shown in Figure 1 the pump is of multi-stage type with three conventional stages, and the pump is terminated at one end by a fluid admission piece 1 through which the pumped liquid is admitted to the first stage of the pump proper. The said fluid admission piece 1 is constructed, in accordance with the invention forming the subject matter of British application No. 5820/41 filed May 5, 1941, with a cavity 2 which houses the coupling 3 between the pump shaft 4 and the shaft of the driving motor, which is not shown, but is bolted to the end flange 5 of the admission piece.

The cavity 2 is formed by a conical wall or socket 6, the forward end of which is bored to form a seating 7a to receive the bearing sleeve 7 for the shaft 4, the bearing being cooled by conduction to the wall 6 and seating 7a and by the pumped liquid which sweeps over the outsides of the seating 7a and wall 6. The heat of the top motor bearing and the end turns of the motor winding is also transmitted to the wall 6 by the liquid contained in the cavity 2 and maintained in a state of turbulence and circulation by the rotating coupling 3. Liquid for lubrication of the pump bearing can pass along the bearing clearance from cavity 2, and the end of the bearing is protected against the entrance of sand or the like into the bearing by the sand bell 8, which has a number of openings 9 to allow adjustment of the pump shaft by means of a tommy bar applied through one of the inlet orifices of the admission piece 1. The admission piece 1 is surrounded by a gauze or perforated screen 10 to prevent the entry of solid matter into the pump through the inlet orifices and passages of the admission piece.

On the pump shaft 4 are successively assembled the distance sleeve 4a, the sand bell 8, and the three impellers 11, each of which comprises an elongated or sleeve-like hub 12 carrying the impeller wheel proper formed by a solid wall or flange 13 and an annular wall 14 which leaves an opening round the hub sleeve 12 to form an annular inlet eye 15. Between the walls 13 and 14 are disposed vanes 16 suitably designed to produce the desired flow of the liquid through the impeller.

Between the impellers 11 are disposed stationary return guide vane members 17, carrying wearing rings 18 of the kind forming the subject matter of British Letters Patent No. 539,373. The return guide vane members 17, comprise a disc wall 17 of less diameter than the end ring of the admission piece 1, having a short hub 19 fitting on the subsequent impeller hub sleeve 12, guide vanes 20, and an annular wall 21 of the same diameter as the end ring of the admission piece 1, whose internal periphery forms a throat 22 opening into the eye of the next impeller 11.

The wearing ring 18 is carried by the annular wall 21 and makes running contact with a shoulder ring on the internal periphery of the annular

wall 14 of the adjacent impeller 11, and between the periphery of the disc walls 17 of the return guide vane members 17, and the wearing rings 18 of the preceding guide vane member 17 are clamped diffuser members comprising suitably curved vanes 23, surrounding the impeller 11, projecting laterally from annular plates or rings 24 (Figures 12 and 13). Packing rings 33 are disposed between the diffuser rings 24 and the peripheries of the annular walls 21 of the return guide vane members 17. The vanes 23 do not extend as far as the periphery of the ring 24, which corresponds in diameter to the rings 21 and the end ring of the admission piece 1, so that an annular space surrounds the vanes 23 which is bounded by the outer casing of the pump, the surface of which thus participates in the guidance of the water flow between stages.

Above the final stage impeller 11 and abutting 20 against the vanes 23 of the last diffuser member, is disposed an annular balance seat 25 carrying a balance ring 26, which makes contact with a wearing ring 27 carried by a balance disc 28 mounted on the shaft 4. The balance disc 28 has an elongated sleeve 48 keyed on shaft 4. The parts keyed to shaft 4 viz: distance sleeve 4a, sand bell 8, impeller hub sleeves 12, and balance disc hub sleeve 48, are axially clamped on shaft 4 by the end nut 29, and finally the sleeve 48 on shaft 4 is fitted into the end cap 30, which contains the top bearing sleeve 49, held in bearing shell 50, and in its cavity accommodates the balance disc 28. The end cap 30 is formed integral with the upper end member or delivery piece 31 of the pump, being connected thereto by webs 44 so as to form delivery channels sweeping over the outer surface of the cap 30, and communicating on the one hand with the discharge opening 32 of the pump and with the 40 annular peripheral space surrounding the diffuser 23, 24 encircling the last impeller 11 on the other hand.

Surrounding the delivery piece 31 is a bolster ring 34 with an interposed packing ring 35, and 45 the whole of the parts assembled on the shaft 4, including not only those keyed to the shaft, but also the interposed annular members, viz: balance seat 25, impellers 11, diffuser members 23, 24, and return vane members 17 with their wearing rings 18, are inserted, as a cylindrical block, into a plain cylindrical casing 36, which fits on, and is fastened to the periphery of the end ring of the admission piece 1 by grub screws 37. The annular interposed members of the pump assembly 55 are then tightened up by means of thrust bolts 38 threaded in a counter supporting ring 39 inserted in the discharge end of casing 36 and secured by grub screws 40. Finally a flanged ring 41 carrying the delivery pipe 42 is secured 60 over the delivery piece 31 of the pump by means of the nuts 43 on bolts 38.

From the foregoing description it will be appreciated that when the bolster ring 34 is tightened up by the thrust bolts 38, the delivery piece 31, and end cap 30, together with the diffuser members 23, 24, wearing plates 18, return vane members 17, and admission piece 1, form a solid cylindrical assembly presenting a smooth cylindrical outer wall fitting within the cylindrical outer casing 36. Dismantling is effected simply by reversing the assembly operations.

It will be understood that the spaces formed between the inner wall of the casing member 36 and the outer edges of the vanes 23 and the annular plates 24 of the diffuser members constitute

annular diversion chambers bounded peripherally by a cylindrical surface normal to the axial. I have found that by keeping the radial dimension of these chambers below a certain fairly small value in conjunction with a suitable pitch of the guide vanes 28, detrimental turbulence in these chambers is avoided.

The invention thus provides a centrifugal pump with a one-piece outer casing which serves the dual purposes of guiding the pumped liquid from a set of diffuser vanes to a set of return vanes and of acting as the main locating means for the pump assembly. It also provides a pump which is simple and robust in construction, of light weight and requiring a minimum of machining, and which is capable of being assembled and dismantled with exceptional ease and rapidity.

What I claim and desire to secure by Letters Patent is:

1. A multi-stage, radial flow centrifugal pump comprising a plurality of bladed impellers arranged in coaxial stages and respectively cooperating with adjacent bladed guide members for controlling the flow between stages, in combination with a one-piece casing surrounding the impellers and guide members in radially spaced relation thereto and providing a cylindrical surface defining within the same circumferential channels outwardly of the guide members for guiding the flow from an impeller into the adjacent guide member as the pumped fluid passes from one impeller to the next.

2. A multi-stage, radial flow centrifugal pump comprising a plurality of impellers arranged in stages in coaxial relation, and associated guide members for controlling the flow of liquid between said stages, said impellers and guide members being threaded in succession upon a central shaft and enclosed by a one-piece cylindrical casing, and the guide members including means for directing the flow in directions both radially and outwardly and radially inwardly in succession between the impellers of successive stages.

3. A centrifugal pump comprising a rotary bladed impeller to produce radially outward flow respecting the axis of rotation, a set of stationary diffuser vanes adjacent to the impeller and in the path of radial flow from the latter, a set of stationary radially inward flow return vanes also associated with said impeller and diffuser vanes in axially spaced relation thereto and coaxial therewith, and a one-piece cylindrical casing enclosing the impeller and vanes aforesaid, said casing serving to guide the flow from the diffuser vanes to the return vanes and also serving as the main locating means of the pump assembly.

4. A centrifugal pump as defined in claim 2, including an end member in one end of the casing provided with fluid inlet orifices and channels leading to a central opening registering with the eye of the first impeller, a bearing shell disposed in said end member in such manner that the outside of the bearing shell is swept by the fluid passing along said channels, and a bearing for one end of the pump shaft, mounted in said bearing shell.

5. A centrifugal pump as defined in claim 2, including an end member in one end of the casing provided with an axial fluid discharge opening, a bearing shell disposed in said end member so that its outside wall is swept by the fluid passing to said discharge opening from the pe-

riphery of the final impeller chamber, and a bearing for one end of the pump shaft supported by the bearing shell.

6. A pump as defined in claim 3, wherein the set of diffuser vanes has an annular form, with the vanes disposed about the periphery of the impeller to guide the liquid in a radially outward direction, and the cylindrical wall of the outer casing thereafter serves to guide the liquid in an axial and peripheral direction, and the set of return vanes subsequently guides the liquid in a radially inward direction.

7. A multi-stage, radial flow centrifugal pump having a plurality of peripherally discharging impellers and intermediate annular fluid-guiding parts, all assembled on the pump shaft to form a cylindrical assembly, said pump including an external one-piece cylindrical casing circumferentially spaced from the impellers, and into which the cylindrical shaft assembly is axially inserted and fastened at its ends, and means for axially clamping the intermediate annular fluid-guiding parts to hold the same stationary while leaving the impellers free to rotate relative thereto.

8. A centrifugal pump as defined in claim 2, in combination with an end member disposed at one end of the casing and provided with fluid inlet orifices and channels leading to a central opening registering with the eye of the first impeller, said end member serving not only as an admission piece for the pumped fluid, but also as a connecting piece between the pump and motor casings.

9. A multi-stage, radial flow centrifugal pump including, in combination, a plurality of radially outwardly discharging impeller members arranged in consecutive stages on a common axis, radially outwardly directing and radially inwardly directing bladed guide members between consecutive stages, and an outer one-piece cylindrical casing radially outwardly spaced from the impellers and providing an interior cylindrical surface for converting the radially outward flow of the fluid from an impeller and its associated outwardly directing guide member into the adjacent inwardly directing guide member.

10. A multi-stage, radial flow centrifugal pump including, in combination, a shaft, a plurality of impeller members mounted in succession on said shaft, a plurality of stationary radially outwardly and inwardly directing guide vane members disposed between successive impeller members, said guide vane members all having cylindrical peripheries of equal diameters and greater than the diameters of the impeller members, and a one-piece cylindrical external casing for said pump fitted on and enclosing said guide vane members and defining an annular fluid-guiding space about the respective impeller members.

11. A multi-stage, radial flow centrifugal pump having a plurality of rotary impeller members arranged in consecutive stages on a common axis, stationary diffusing vane members and return vane members disposed consecutively in back-to-back abutting relation to each other between each pair of impeller members, and a casing enclosing the impeller members and vane members and providing cylindrical fluid-guiding surfaces concentric with the pump shaft between said diffuser and return vane members to direct the liquid flow from the diffuser vane members to the return vane members consecutively between the impeller stages.

12. A multi-stage, radial flow centrifugal pump including, in combination, a shaft, a plurality of impeller members mounted in succession on said shaft, a plurality of annular return vane members respectively located between said impeller members, hubs on said impeller members located in and by said annular return vane members, an-

5 nular diffuser vane members also respectively located between said impeller members and displaced axially from said return vane members in abutting relation thereto, and a one-piece cylindrical casing fitting the external peripheries of said diffuser and return vane members.

GILES P. E. HOWARD.
